[57] CLAIM

The ornamental design for a combined bottle and cap, as shown and described.

DESCRIPTION

FIG. 1 is a front elevation of a combined bottle and cap showing our new design, the rear elevation is a mirror image thereof;

FIG. 2 is a top plan view thereof;

FIG. 3 is a front elevation of the bottle shown without the cap for clarity of illustration;

FIG. 4 is a side elevation as seen from the left of FIG. 3;

FIG. 5 is a top plan view of FIG. 3;

FIG. 6 is a side elevation as seen from the right of FIG. 3;

FIG. 7 is a rear elevation of FIG. 3; and,

FIG. 8 is a bottom plan view of FIG. 3.
